Thomas A. Harkins

UNITED STATES PATENT OFFICE

2,538,453

SLITTER DEVICE FOR WIRE INSULATION
OR THE LIKE

Thomas A. Harkins, Los Angeles, Calif.

Application October 6, 1947, Serial No. 778,202

7 Claims. (Cl. 30—91)

1

My invention relates to slitting devices and more particularly to apparatus adapted for cutting a slit within the insulation of wire covering.

Accordingly an object of my invention is to provide a slitting tool or device, having a housing mounted upon a suitable handle, said housing having a bracket provided with a suitable roller adapted for guiding the wire or cable thereover, also, said housing having a retractable plunger means provided with a slitting tool or knife, with which a slit may be cut within the insulation of said wire or cable, when pressed into said insulation and pulled lengthwise over said roller.

Another object of my invention is to provide said slitting tool with a self-centering and self-locating adaptor provided with said slitting tool or knife, and adapted for positioning and for holding said knife and its cutting edge at the center of said insulation, and when said wire or cable is placed over the guiding roller, thereby preventing off-center cutting in said insulation and also preventing the damage to a wire encased therein.

A further object of my invention is to provide said slitting tool with a retractable plunger means and a frictionally engaging brake means, adapted for holding said plunger means in locked position when set and when cutting the slit within the insulation of said wire or cable.

Another object of my invention is to provide said plunger means of said slitting tool with a depth gage ring, which is adjustably mounted thereon, and thereby providing means for regulating and controlling the depth of the slit in said insulation of the wire or cable.

A further object of my invention is to provide said slitting tool or device with a retractable plunger means, which is equipped with a removable and adjustable slitting tool or knife, further, said device having a plunger engaging brake means adapted for holding said plunger means together with said slitting knife in a set position, and also, having suitable means for releasing said plunger means from its slit cutting position into its upwardly normal position, and in addition said brake release means having a regulating pin associated therewith, for allowing said plunger engaging brake means to be held in an engaging position when set for cutting a predetermined depth in the wire or cable insulation, or, for neutralizing the action of said brake means, whereby any desired depth of slit in said wire or cable insulation may be cut, and thereby controlling said slit cutting operation when said wire or cable is coated with an irregular insulation,

2

which may be the thickness, diametrical shape or configuration.

Another object of my invention is to provide said slitting tool or device with a suitable plunger controlling means adapted for controlling the depth cutting action of the slitting knife, which may be a depth of slit set position or a manually regulated depth of slit in said insulation.

A further object of my invention is to provide said slitting tool or device with a retractable plunger means, said plunger having spring means associated therewith for maintaining the same in the uppermost position, and in addition said plunger having means for regulating a downward travel of said plunger, thereby preventing the knife cutting edge from penetrating deeper into the insulation of a wire or cable, than the required depth originally set by means of said regulating means.

Another object of my invention is to provide said retractable plunger means with a removable and interchangeable cartridge means, said cartridge means having a slitting knife adjustably mounted therein, also said plunger means having an ejecting spring mounted therein for ejecting said cartridge means from its position when released by the mounting screw, and thereby facilitating the handling and knife edge length setting operation, when necessary or required.

My invention also has for its objects to provide such means that are positive in operation, convenient in use, easily installed in a working position and easily disconnected therefrom, economical in manufacture, relatively simple, and of general superiority and serviceability.

The invention also comprises novel details of construction and novel combinations and arrangements of parts, which will more fully appear in the course of the following description. However, the drawings merely show and the following description merely describes embodiments of the present invention, which are given by way of illustration only.

Reference is now had to the accompanying drawings, in which the similar reference characters denote the same parts.

In the drawings:

Fig. 1 is the side elevational view of the slitter device.

Fig. 2 is the front elevational view thereof.

Fig. 3 is a fragmentary and slightly enlarged sectional view of the housing, showing the retractable plunger and the locking mechanism in position, taken on the line 3—3 of Fig. 2.

Fig. 4 is another sectional view of the plunger, taken on the line 4—4 of Fig. 3.

Fig. 5 is a fragmentary sectional view of the lock ring pivot section, taken on the line 5—5 of Fig. 3.

Fig. 6 is another fragmentary sectional view thereof, showing the lock ring trip lug member, taken on the line 6—6 of Fig. 3.

Fig. 7 is a horizontal sectional view of the housing and the plunger, showing the locking ring in position, taken on the line 7—7 of Fig. 4.

Fig. 8 shows another horizontal sectional view of said housing, taken in the direction of the arrow 8—8, of Fig. 3.

Fig. 9 is a fragmentary sectional view of the tripper pin member, showing the same in relation to the mounting pin, taken on the line 9—9 of Fig. 3.

Fig. 10 is a horizontal sectional view of the plunger member, showing the slots in relation to the mounting pin, taken on the line 10—10 of Fig. 3.

Fig. 11 shows the bottom view of the housing and the plunger member, showing a plate mounted upon the end of the housing, and showing the structure in a modified form.

Fig. 12 shows a fragmentary sectional and partly vertically elevational view of the plunger control and release mechanism of the device, showing the same in nearly the same position as disclosed in Fig. 3, and showing the same in a modified form.

Fig. 13 is a horizontally sectional and partly fragmentary view of the tripper pin extension, taken on the line 13—13 of Fig. 12.

Describing my invention more in detail, in its broader aspects, said invention comprises a housing 2 having a suitable extension 4, the upper section of which is provided with a suitable handle member 6, which extends outwardly and rearwardly therefrom, as shown.

Said housing 2 is provided with a suitably bored out section 3, wherein a plunger member 10 is slidably mounted, and which is held in position by means of a pin member 12 passing through a pair of locating slots 14 which extend into the upper section 10 of said plunger, said slots 14 being adapted for guiding said plunger member into a downward and retractable position, and also for holding said plunger member 10 in place.

Said pin member 12 is provided with a threaded head 16 which is secured in said housing 2, while the pin end 18 extends into said housing for engaging a milled out section 20, which is disposed within the shank member 22 of a tripper pin member 24, the operation and the purpose of which will be presently described.

The plunger member 10, in its preferred form, is made out of suitable tubing, and comprises the upper end section 26 which terminates with a plunger cap member 28, also, said plunger having the outer surface section thereof provided with a suitable thread 30, which is adapted for engaging and for mounting a gage ring 32 thereon, so that the same may be adjusted to any suitable position and thereby regulating the downward movement and the downward position of said plunger member 10.

The lower section 34, of said plunger member 10, is provided with a suitable locating bushing 36, the lowermost end of which lies in close proximity to the end section 34, as shown in Fig. 3, also, said bushing member 36 is provided with a suitable locating slot 38 which is adapted for guiding a slitting knife 40 into position.

Said bushing 36 is held in position and within said plunger member 10 by means of a suitable mounting pin member 42, as shown.

Said slitting knife 40 is also held in position by means of a self-centered cartridge member 44, the lower end of which is tapered as at 46, for engaging the end edge of said plunger member 10 at said lower section 34, while the upper end 48, of said cartridge, is fitted into said bushing 36, and wherein said cartridge member 44 is held in position by means of a set screw member 50, as shown in Fig. 4.

It may then be noted, that said knife 40 is provided with a wide shank 52 at the upper part or section thereof, which fits snugly into the lower section 34 of said plunger member 10, and thereby preventing said knife from tilting when a pressure is applied thereto, and while cutting a heavy cable sheath, lead covering, or heavy synthetic rubber, plastic or the like.

In order to adjust the position of the knife point 54, said cartridge 44 is provided with a suitable adjusting set screw 56, and also, for facilitating the removal of said cartridge from its set position, a suitable pressure spring 58 is provided, as shown in Figs. 3 and 4, and which is supported in its compressed position by means of said pin member 42.

Also, for holding and for maintaining an uppermost position of said plunger member 10, a suitable spring member 60 is provided within said upper end section 26, one end of which resting against the underside section of said cap member 28, while the other end thereof bears upon said pin member 12, as shown.

In order to hold said plunger member 10 in any set position, when pressed downwardly, a suitable lock ring 62 is provided in said housing 2, said ring being mounted therein at the lowermost end section thereof, which comprises a ring member 64 having a suitable pivot end 66 and a trip lug member 68, as shown in Fig. 7.

Said lock ring 62 is loosely disposed within a recess 70, having a pivot end 66 supported upon a rest ledge 72 and is held in place by means of a suitable boss member 74, which is provided upon the upper surface of a plug member 76, while said trip lug member 68 is supported in the uppermost angular position by means of a spring 78, which is disposed within a groove 80, as shown.

The inside bore of said ring 62 is slightly larger than the outside diameter of said plunger member 10, which allows a slight angular position thereover while the pivot end 66 is held in position and the trip lug member thereof is pressed upwardly by said spring 78, which imposes a binding friction upon said plunger member 10 and thereby holding said plunger in any set position.

In order to release the binding friction of said lock ring 62 then said tripper pin member 24 is employed, which is mounted within a suitable socket 82, see Fig. 3, of which the lowermost extension 84 engages said trip lug member 68, said milled out section 20 including said recess 70 and said socket 82 having sufficient clearance, so that when pressing the tripper head 86 downwardly, then the frictional binding of said lock ring 62 over said plunger member 10 is released, whereby the compressed spring member 60 causes said plunger to retract into its uppermost normal position.

For guiding and for holding a wire or cable in place and beneath said knife point 54, a suitable step roller 88 is provided, which is mounted

within the loop 90 of a bracket 92 and which is held in position upon the side section of said housing 2, by means of suitable screws 94.

For preventing said bracket 92 from shifting out of alignment, the upper section thereof is mounted within a suitable recess 96, and for preventing dragging of the wire or cable when placed over said roller 88, a suitable pin 98 is provided for mounting said roller thereon and for permitting said roller to revolve freely thereover.

As shown in Fig. 12, said tripper pin 24, in its construction and operation, is shown in a modified form, for allowing said knife 40 particularly the knife point 54, to be set at a predetermined position, and also, for allowing the use of said knife point in special cases, when the insulation of wire or cable is of irregular shape, structure, thickness or configuration.

To that end, said shank 22 of said tripper pin, is provided with a recess 104, which, in addition of allowing said pin end 18 to hold the same in place and position, said pin 24 is allowed to be turned in the socket member 82.

Also, the extension 84 of said tripper pin 24 is provided with a suitable arresting groove 106 for accommodating therein a screw point 108 extending out of a set screw member 110, which, in this position and location, said ring 64 is tilted downwardly, remaining in a neutral and inactive position, and thereby allowing said plunger 10 to remain free of frictional resistance afforded by said ring 64, and in the manner hereinbefore described.

When said ring 64 is held in a neutral position, then said plunger 10 may be pressed downwardly to any desired point of location, the position of which may be regulated by the thumb pressure imposed upon said cap member 28, and thereby allowing said slitting knife 40 to cut into the insulation of wire or cable, of irregular shape, thickness or configuration.

When it is desired to secure a predetermined depth cut control of said plunger 10, said tripper pin 24 is turned in said socket 82, to an approximate 90 degrees, which allows said screw point 108 to enter a longitudinal slot 112, thereby releasing said ring 64 from its set and inactive position, allowing said ring to pivot upon said pivot end 66, the position of which being supported by said spring 78, so that a frictional grip upon the plunger 10 may be had, in a similar manner as previously described.

Said longitudinal slot 112 is arranged to permit a downward movement of said tripper pin 24, which movement is used for releasing said grip on said plunger member 10, and thereby allowing said plunger to be retracted into its normal upward position, when released, the upward movement thereof being supported by said spring member 68.

In addition, it may be noted, that in place of employing said plug member 76, which is used for holding said lock ring member 62 in position, and also for guiding and for maintaining a rigid position of said plunger 10, when in its downward and lowermost position, said housing 2, at its extension 4, may, if so desired, be provided with a suitable locating plate 138, which is held in place by means of screws 140, and which in use and application will accomplish and will serve the same useful purpose as hereinbefore pointed out.

While I have thus described my invention with great particularity, it will be clear that the same may be modified throughout a wide range.

I, accordingly, do not propose to be limited to the exact details of construction herein shown on the drawings and described in the specification, but reserve the rights in practice to make the necessary changes and modifications therein, which may come within the scope of the appended claims.

I claim as my invention:

1. In a slitting tool of the class described, comprising, a housing, a handle extending outwardly from said housing, a bracket mounted on and connected to said housing having a loop extending endwardly therefrom, a roller mounted in said loop, a retractable plunger member slidably mounted in said housing, a removable cartridge mounted in said plunger, a slitting knife in said cartridge, a frictional ring means in said housing, a spring in said housing for supporting one end of said ring means and for holding the same in a frictional engagement with said retractable plunger member, thereby holding said plunger member in position when pressed downwardly, a tripping means in said housing for releasing said plunger member from the downwardly held position, and a spring member in said plunger member for forcing said plunger member upwardly and into its normally upward position.

2. In a slitting tool of the class described, as disclosed in claim 1, wherein, said tripping means is provided with guiding means for guiding said tripping means when releasing said frictional ring means from its frictional engagement and locked position over said plunger member, and means in said tripping means for neutralizing the grip imposed upon said plunger member by said ring means, thereby allowing said plunger member to be pressed downwardly and into a cutting position, and also, for releasing said plunger member into its normally upward position.

3. A slitting tool of the class described, comprising, a housing, a handle extending outwardly from said housing, a retractable plunger means mounted in said housing, a lock ring means in said housing for frictionally engaging said plunger means, a bracket means connected to said housing and having a roller revolvably mounted therein for holding a wire or cable in position, a slitting knife in said plunger means for slitting the insulation in said wire or cable, and tripper means in said housing for releasing said lock ring means from the frictional position over said plunger means and thereby releasing said plunger means from the downwardly set position.

4. In a slitting tool of the class described comprising a housing, a handle extending sidewardly from said housing, a retractable plunger means slidably mounted in said housing, means in said plunger for maintaining the retractable position of said plunger, and means in said housing for frictionally engaging said plunger and thereby holding same in any set position, the combination of, a locating bushing in the lowermost end of said plunger, a locating groove in said bushing, and a concentric cartridge means in said plunger carrying a slitting knife and mounted in said bushing thereby locating the cutting position of said slitting knife, and means in said plunger for holding said cartridge in position.

5. In a slitting tool of the class described, as disclosed in claim 4, wherein an adjustable set screw is provided in said cartridge, for adjusting the knife point of said slitting knife, and spring means in said locating bushing for eject-

ing said cartridge from its set position, when released by said holding means in said plunger.

6. In a slitting tool of the class described, as disclosed in claim 4, wherein, a tripper pin means is provided in said housing for releasing said frictionally engaging means for said plunger, and thereby releasing said plunger and said slitting knife from the downward position of said plunger and the cutting position of said knife, respectively.

7. In a slitting tool of the class described, as disclosed in claim 4, wherein a plug member is provided in said housing, a boss member in said plug for holding said frictionally engaging ring means in tiltable position, a groove in said plug member, and resilient means in said groove

whereby the uppermost tilted position of said frictionally engaging plunger means may be maintained and thereby holding said plunger member in its set position.
